UNITED STATES PATENT OFFICE

2,442,189

FLASH CONTROL SYSTEM

Spencer L. Bellinger, Lake Luzerne, N. Y., assignor
to General Electric Company, a corporation of
New York

Application January 4, 1946, Serial No. 639,127

4 Claims. (Cl. 320—1)

1

This invention relates to control systems, more particularly to systems for producing illuminating flashes, and it has for an object the provision of a simple, reliable, inexpensive and improved system of this character.

In the study and analysis of high speed mechanical motions there is need for means for photographing these motions in a period of time which is sufficiently short to "freeze" the mechanical action. For example, in the making of shadowgraph photographs of objects and gases, the object or gas is frequently moving at a speed in excess of the speed of sound and sometimes at a speed as high as 3000 ft. per second. In order to "freeze" motion at this speed, an illuminating flash of extremely brief duration is required, and accordingly a further object of this invention is the provision of a system for producing an illuminating flash of which the photographically effective duration is a fraction of a microsecond.

Another object is the provision of a flash control system having no electric valves in the flash-producing discharge circuit but in which the discharge circuit is controlled by means of an electric valve.

One advantage of the arrangement in which no electric valve is included in the discharge circuit is that the high resistance of such electric valve is eliminated. This results in a very substantial shortening of the actual duration of the discharge and the duration of the photographically effective portion of the discharge.

Still another object of the invention is the provision of a flash control system in which the enclosed area of the spark discharge circuit loop and its inductance are reduced to a minimum.

In carrying the invention into effect in one form thereof, a capacitor is provided together with a source of unidirectional voltage for charging the capacitor to a desired predetermined voltage. A pair of spark discharge gaps are connected in series directly across this capacitor. The gaps are of such dimension that the combined breakdown voltage is substantially in excess of the predetermined voltage to which the capacitor is charged and the breakdown voltage of each gap individually is substantially less than this predetermined voltage. In addition, a voltage divider comprising a relatively high resistance is connected in parallel with the capacitor and the gaps. A connection from an intermediate point on the divider to the central electrode of the gap is provided so that each of the gaps is paralleled by an equal portion of the voltage divider resistance. Each of these portions of the divider has

2

a voltage drop which is less than the breakdown voltage of the gap with which it is connected in parallel. A suitable electric valve and current limiting resistance are connected in parallel with one of the portions of the divider and its corresponding gap. This valve serves to initiate the breakdown of the gap in such a manner that a flash-producing discharge takes place across both gaps.

10 For a better and more complete understanding of the invention, reference should now be had to the following specification and to the accompanying drawing of which Fig. 1 is a simple, diagrammatical illustration of an embodiment of the invention, and Fig. 2 is a diagram which illustrates the physical arrangement of the spark gaps with respect to the capacitor.

Referring now to the drawing, a capacitor 1 is arranged to be charged from a suitable D.-C. 20 source, such as represented by the positive supply line 2 and the negative supply line 3. A resistor 4 is connected in series between the positive line 2 of the source and the positive terminal of the capacitor for limiting the charging current. A 25 voltage divider comprising resistors 5, 6, and 7 is connected across the source. In a typical case the voltage of the source 2—3 may be assumed to be 15,000 volts. It may also be assumed that the capacitor 1 has a capacitance of .12 mfd. and 30 that it is to be charged to a voltage of 14,900 volts. Accordingly the capacitor 1 is connected to points 5a and 6b on the voltage divider having a potential difference of 14,900 volts. The supply conductor 3 is connected to ground. The voltage drop between the point 6b of the voltage divider 35 and the lower terminal 7a is such a small amount that for all practical purposes the lower plate of the capacitor 1 is effectively connected to ground.

As shown in Fig. 2, the capacitor is mounted 40 within a suitable enclosure 8 upon which is mounted an insulating bushing 8'. A pair of spark gaps 9 and 10 are connected in series relationship directly across the capacitor. The electrode 9a of gap 9 is directly connected to the positive terminal 1a of the capacitor which is brought out through the insulating bushing 8'. The electrode 9b of gap 9 and electrode 10a of gap 10 are directly connected together by means of a short, heavy conductor 11 and may be considered as comprising a single central electrode. The remaining electrode 10b of gap 10 is directly connected to the lower ground terminal of the capacitor.

The junction point 6a of the two resistors 5 and 55 6 is connected to the short conductor 11 and is

thus connected to the central electrode of the two spark gaps.

Although the resistance of the resistors 5 and 6 may be any suitable value, it is preferably relatively high. In a typical case the resistors 5 and 6 may each have a resistance of 100 megohms. Thus, with the capacitor 1 charged to a voltage of 14,900 volts, current flowing through the voltage divider is .0000745 ampere and the voltage drop across each resistor is 7,450 volts.

The gaps should have a combined breakdown voltage which is substantially greater than the predetermined voltage to which the capacitor 1 is charged and should have an individual breakdown voltage which is substantially greater than the voltage drop across the portion of the voltage divider with which it is connected in parallel. Thus, the electrodes of the gaps are properly set with a spacing such that neither gap will break down with a voltage of 7,450 volts supplied across it. For the constants assumed for the capacitor 1 and the resistors 5 and 6, a proper spacing of the electrodes would provide an individual breakdown voltage of 8,500 volts for each gap.

In parallel with the resistor 6 is connected a suitable electric valve 12. Although this electric valve may be of any suitable type it is preferably a thyratron. The anode 12a of the thyratron is connected through a suitable resistor 13 to the point 6a of the voltage divider, and the cathode 12b is directly connected to the negative terminal 6b of the resistor 6. The grid 12c of the thyratron is connected by means of a conductor 14 to the grounded terminal 7a of the voltage divider and thus the grid is maintained at a voltage which is negative with respect to the voltage of the cathode by the amount of the voltage between the points 6b and 7a of the voltage divider. In a typical case the resistor 13 may suitably have a resistance of .1 megohm.

For the purpose of initiating conduction of the thyratron, a capacitor 15 is provided having one terminal connected to the cathode 12b together with a manually operated switching device 16 for connecting the other terminal of the capacitor to ground. A resistor 17 is connected in parallel with the capacitor 15.

With the foregoing understanding of the elements and their organization, the operation of the system itself will be readily understood from the following detailed description. When the conductors 2 and 3 are energized, the capacitor 1 is charged up to a voltage which was assumed to be 14,900 volts. The voltage across each of gaps 9 and 10 is 7,450 volts which is less than the breakdown voltage of each gap. Consequently, no discharge takes place across the gaps.

The voltage of the grid 12c of the thyratron is maintained approximately 100 volts negative with respect to the voltage of the cathode in order to maintain the valve non-conducting when the switch 16 is open.

The discharge across the gaps 9 and 10 is initiated by closing the switch 16 to connect the lower terminal of the capacitor 15 to ground. Since the capacitor 15 cannot charge instantly, the voltage of the upper plate follows that of the lower plate, i. e. for a brief instant it has ground potential and thus the voltage of the cathode 12b is lowered sufficiently with respect to the voltage of the grid to render the thyratron conducting.

Since the resistor 5 has a very high resistance, e. g. 100 megohms, the current conducted through the resistor 13 and the thyratron 12 produce such a large voltage drop across the resistor 5 that

the potential of the point 6a approaches ground potential. Thus, the voltage applied across the gap 9 is nearly 14,900 volts which is substantially in excess of its breakdown voltage. Consequently, the gap breaks down but the current flow across the gap 9 is limited by the resistor 13 to .15 ampere. However, this current flowing through the resistor 13 produces a voltage drop across the resistor of approximately 14,900 volts 10 and thus the voltage across the gap 10 is raised to approximately 14,900 volts which is in excess of the breakdown voltage. Consequently, the discharge circuit from the positive terminal of the capacitor 1 is completed through the gaps 9 15 and 10 to ground and the discharge produces a brilliant flash of extremely brief photographically effective duration, e. g. approximately $\frac{1}{4}$ microsecond. Since the major light output of either gap cannot occur until the other gap has broken down to permit the heavy surge of current to flow, there is no effective time lag between the peak emissions of light in the two gaps.

After the discharge across the gaps takes place, the voltage of the anode of the thyratron is reduced to such a low value that conduction is extinguished. Following the closing of the switch 16, the capacitor 15 is charged and thus the voltage of the cathode 12b regains its former value which is positive with respect to the voltage 30 of the grid 12c. Thus, the flash cannot be repeated until the starting switch 16 is opened to permit the capacitor 15 to discharge through resistor 17 and to leave the system in a reset condition.

35 Although in accordance with the provisions of the patent statutes this invention is described as embodied in concrete form and the principle thereof has been explained together with the best mode in which it is now contemplated applying 40 that principle, it is to be understood that the elements shown and described are merely illustrative and that the invention is not limited thereto since alterations and modifications will readily suggest themselves to persons skilled in 45 the art without departing from the true spirit of this invention or from the scope of the annexed claims.

What I claim as new and desire to secure by Letters Patent of the United States, is:

50 1. A flash producing system comprising a capacitor, means for charging said capacitor to a predetermined voltage, means providing a pair of spark discharge gaps connected in series across said capacitor and having a combined breakdown voltage substantially greater than said predetermined voltage, a voltage divider comprising a resistor of relatively high resistance connected in parallel with said capacitor and having a first portion connected in parallel with a first one 55 of said gaps and a second portion connected in parallel with the second of said gaps, each of said portions having a voltage drop substantially less than the breakdown voltage of the parallel gap, means comprising an electric valve connected in parallel with said first portion for effecting an initial discharge across said second gap, and a resistance included in the anode-cathode circuit of said valve for limiting said initial discharge to a value insufficient to produce an effective 60 flash and for increasing the voltage across said first gap above its breakdown voltage thereby to effect a main discharge across both said gaps.

65 2. A flash producing system comprising a capacitor, means for charging said capacitor to a predetermined voltage, means providing a pair of

spark discharge gaps connected in series across said capacitor and having a combined breakdown voltage substantially greater than said predetermined voltage and having individual breakdown voltages substantially less than said predetermined voltage, a voltage divider comprising a resistor having a relatively high resistance connected across said capacitor and having a first portion connected in parallel with a first of said gaps and a second portion in parallel with the second of said gaps, a normally non-conducting electric valve having its anode-cathode circuit connected in parallel with said second gap and said second divider portion, a current limiting resistance connected in the anode-cathode circuit of said valve, and means for rendering said valve conducting to increase the voltage across said first gap above its breakdown voltage to initiate a relatively slow rate discharge across said first gap and thereby increase the voltage across said second gap above its breakdown value to effect a relatively high rate discharge across both said gaps.

3. A flash producing system comprising a capacitor, means for charging said capacitor to a predetermined voltage, means providing a pair of spark discharge gaps connected in series across said capacitor and having a combined breakdown voltage substantially greater than said predetermined voltage, a voltage divider comprising a resistor of relatively high resistance connected in parallel with said capacitor and having a first portion connected in parallel with a first one of said gaps and a second portion connected in parallel with the second of said gaps, each of said portions having a voltage drop substantially less than the breakdown voltage of the parallel gap, a normally non-conducting electric valve having its anode-cathode circuit connected in parallel with said first portion, means for rendering said valve conducting to effect an initial discharge across said second gap, and a resistance included in said anode-cathode circuit for limiting said initial discharge to a value insufficient to produce an effective flash and for increasing the voltage across said first gap above its breakdown voltage to complete a main discharge path and effect a main discharge through both said gaps.

4. A flash producing system comprising a main

capacitor, means for charging said capacitor to a predetermined voltage comprising a pair of supply conductors, a voltage divider connected across said conductors comprising a relatively high resistance connected across said capacitor and a relatively low resistance, means providing a pair of spark discharge gaps connected in series across said capacitor and having a combined breakdown voltage substantially greater than said predetermined voltage and each of said gaps having a breakdown voltage substantially less than said predetermined voltage, a connection from an intermediate point of said high resistance of said divider to an intermediate point in the circuit between said gaps so that each of said gaps is paralleled by a different portion of said high resistance, an electric valve provided with an anode, a cathode and a control grid and having its anode-cathode circuit connected in parallel with a first one of said gaps and the corresponding portion of said high resistance, a connection from the grid of said valve to a point on said divider having a voltage that is negative with respect to the point of connection of said cathode, means for rendering said valve conducting to increase the voltage across the second of said gaps above its breakdown value to effect an initial discharge of said capacitor, said means comprising a normally open connection including a capacitor between said cathode and a point on said divider having a voltage that is negative with respect to the voltage of said cathode, a switch for completing said normally open connection, and a resistance included in the anode-cathode circuit of said valve for limiting said initial discharge to a relatively low rate and to raise the voltage across said first gap above its breakdown value to effect discharge of said main capacitor across both said gaps.
